UNITED STATES PATENT OFFICE.

ROBERT GALBRAITH, OF GREEN ISLAND, ASSIGNOR TO THE N. S. VEDDER PATTERN WORKS, OF TROY, NEW YORK.

RESERVOIR COOK-STOVE.

SPECIFICATION forming part of Letters Patent No. 228,454, dated June 8, 1880.

Application filed March 5, 1880. (No model.)

To all whom it may concern:

Be it known that I, ROBERT GALBRAITH, of Green Island, in the county of Albany and State of New York, have invented certain Improvements in Reservoir Cook-Stoves, of which the following is a specification.

My invention relates to improvements in reservoir cook-stoves of the kind having a rear top pot-hole plate immediately over a heating-flue space and a water-reservoir fitting upon said rear top plate and adapted to be removed from the pot-holes therein, so as to permit the pot-holes to be used for other purposes.

The principal objects of my improvements are, first, to provide means whereby the water-reservoir can be turned off in a horizontal plane from over the pot-holes in the rear top plate about a center at one side of the stove and at one front corner of the reservoir; second, to provide means whereby the reservoir can be firmly attached at its two front corners to the side parts of the stove when the reservoir shall be over the pot-holes in the rear top plate, and shall be adapted to be swung off horizontally to the right side and to the left side of the stove from over said pot-holes, and to be entirely detached from the stove; third, to provide a removable side extension of said rear pot-hole plate to help support the reservoir when the latter shall be turned off from over the pot-holes in that plate; fourth, to form the reservoir of an inner vessel and an outer casing supporting the bottom of the vessel, and open for the passage of hot air or gas from the space under the rear pot-hole plate, through the pot-holes therein, and into a space between the walls of the vessel and its casing; and, finally, to provide means for hinging and securing the casing to the stove.

I attain these objects by the means represented in the accompanying drawings, in which—

Figure 1 is a perspective view of a cook-stove having a rear low-down pot-hole plate with a water-reservoir resting thereon, and secured by hinge-joints at its front corners to the adjacent side parts of the stove. Fig. 2 is a perspective view of the same reservoir cook-stove with the reservoir turned off from over the pot-holes in the rear top plate and

about the hinge at one front corner of the reservoir, the pivot-pin of the hinge at the other front corner being removed. Fig. 3 is a vertical section of a portion of the same with the reservoir in the position shown in Fig. 1, at 55 the line *z z* in Figs. 5, 6, and 10, and elevation of some parts in rear of that line, the pivot-pin of one hinge only being inserted. Fig. 4 shows a vertical section of the same at the line *y y* in Figs. 5 and 6 when the reservoir is 60 composed of an inner vessel for water and an outer casing. Fig. 5 is a horizontal section of the same at the line *x x* in Figs. 3, 4, and 6, and plan of some parts below that line. Fig. 6 is a vertical section of the same at the line *w w* in Figs. 3, 4, and 5. Fig. 7 is a plan of the under side of the reservoir when composed of the outer casing and vessel therein. Fig. 8 shows a detached plan and edge view of a removable annex to the rear pot-hole plate. Fig. 70 9 is a view of one of the removable pivot-pins of the hinges by which the reservoir is secured to the stove. Fig. 10 is a central longitudinal vertical section of the rear portion of the same reservoir cook-stove shown in Figs. 1 and 2 75 when the reservoir consists merely of a watertight vessel or chamber.

Like letters refer to similar parts in the different figures.

A is the main top pot-hole plate, and B is a 80 rear low-down pot-hole plate immediately over a fire-flue space, C, essentially the same as in various cook-stoves made before my invention. In Fig. 2 the pot-holes in the plate B are closed by removable covers *a a'*, and in Figs. 85 4, 5, 6, and 10 the same pot-holes *b* are shown open.

E is the whole water-reservoir, which has its bottom flat or shaped to fit closely upon the rear plate, B, and cover the pot-holes therein, and with its front side, *s*, opposite and close to the upper rear end plate, *r*, of the stove. The reservoir E is to consist of a simple watertight vessel or chamber, as shown in section in Fig. 10, or of an outer casing, E', preferably of cast-iron plates, and an inner watertight vessel, D, preferably of sheet metal, an example being shown in section in Figs. 4, 5, and 6.

In order that the whole water-reservoir may 100

be easily turned off from over the pot-holes in the rear top plate and supported at one side of the stove, essentially as shown in Fig. 2, to permit the pot-holes to be used for ordinary culinary purposes, I secure one front corner part of the reservoir to the adjacent side part of the stove by means of any suitable known kind of hinge or pivot joint. In the drawings this joint is shown, as I commonly prefer, composed of a strong lug or lugs, *c* or *c'*, fast on one outer front corner part of the reservoir, and a corresponding lug or lugs or projecting parts, *d* or *d'*, fast on the adjacent side part of the stove, and a pivot-pin, *f*, Fig. 9, inserted through corresponding perforations *g* through the two halves *c d* or *c' d'* of the hinge, essentially as indicated in Figs. 2, 3, and 5.

In the reservoir cook-stove represented in the drawings the two outer front corner parts of the reservoir have fast thereon the two half-hinge parts *c* and *c'*, and the two side parts of the stove have the corresponding other two half-hinge parts *d* and *d'* fast thereon, so that when the reservoir is upon the rear pot-hole plate, *B*, as shown in Figs. 1, 3, 4, 5, 6, and 10, with two pivot-pins, *f*, inserted through the coinciding perforations *g* in the two pairs of half-hinges, the reservoir will be thereby firmly secured at its two front corners to the two side parts of the stove, for stable use on the rear pot-hole plate when the stove shall be used in boats or vessels or in railway-cars. Also, by having only one pair of the half-hinges, *c d*, or the other pair, *c' d'*, united by a pivot-pin, *f*, as indicated in Figs. 2, 3, or 5, the reservoir can then be turned off from over the pot-holes in the plate *B* about the hinge having the pivot-pin therein, and thereby supported at one side of the stove, as shown in Fig. 2, or at the other side, as indicated by dotted lines at *E*² in Fig. 5, so as to permit the rear pot-hole plate, *B*, to be used with the least practicable interference from the turned-off reservoir, according to the different positions in which the stove shall be placed in the kitchen. Also, upon removing the pivot-pins from both of the hinges the whole reservoir can be freely taken off from the rear pot-hole plate, *B*, and used on the main pot-hole plate *A* of the stove.

To provide temporary additional support for the reservoir when the same shall be turned off from over the pot-holes in the plate *B*, I provide an extension-piece, *F*, detachably secured at that side edge of the plate *B* over which the reservoir is turned off, and with the plane of the upper surface of the rear pot-hole plate so that the turned-off reservoir shall rest upon said extension-piece.

The part *F* is detachably secured to the stove or plate *B* by any suitable means. For that purpose I commonly prefer to make the turned-down side-edge parts of the plate *B* with socket-apertures *h*, Fig. 5, and the part *F* with corresponding lugs *i*, Fig. 8, shaped and arranged to fit into and firmly engage with the said socket-apertures and turned-

down side parts of the plate *B*, substantially as shown by Figs. 4 and 5.

When the reservoir is composed of the inner vessel, *D*, and outer casing, *E'*, the latter is preferably made, as shown in Figs. 4, 5, 6, and 7, of enough greater width and length internally than the exterior of the vessel *D* to thereby form a space, *G*, between the walls *j* of the vessel and the walls *k* of its casing. The bottom of the casing *E'* is also preferably made with a part or parts, *l*, extending under the vessel *D*, and with an opening or openings, *m*, all shaped and arranged so that while the part or parts *l* shall support the bottom *n* of the vessel and keep the latter from contact with the pot-hole plate *B* in sliding the casing to and fro on that plate the opening or openings *m* in the bottom of the casing will permit the hot air or gas to rise and pass from the space *C* through the pot-holes *b* into contact with the bottom of the vessel *D* and into the space *G*, and there in contact with the walls *j* of the vessel, essentially as indicated in Figs. 4 and 6.

The casing *E'* has the two half-hinges *c c'* fast on its two front corners, and preferably has its top *o* fast to its walls *k* and formed with internal ledges, *p*, in which can rest the rim of the vessel *D* and the removable cover *H*, so that upon lifting off the cover the vessel *D* can be drawn out of the casing for cleaning and to permit the insertion of another vessel.

The stove with the casing *E'* hinged at one front corner to one side part of the stove, can be made and sold without the vessel *D*, and can thus be used to warm, heat, bake, and cook food in any suitable known kind of pan or vessel placed in that casing, to which proper different degrees of heat can be imparted from the plate *B* by turning and thereby adjusting the hinged casing *E'* more or less over and off from that heating-plate.

I am aware that prior to my invention portable devices for use on the pot-hole plate of a cook-stove have been made with an inner water-holding vessel and an outer casing open at its bottom and surrounding and supporting the inner vessel, with a space for the circulation of heated air or gases from the fire under the pot-hole plate through the pot-holes and into the space between the walls of the vessel and its casing; and I do not claim that construction.

I am also aware that before my present invention reservoir cook-stoves having a pot-hole plate in rear of the exit-pipe, and lower than the main pot-hole plate, and immediately over a fire-flue space, have had a removable water-reservoir fitting upon said rear pot-hole plate and around and over the pot-holes therein, and with the front side of the reservoir close to the upper rear plate of the stove, and that in some such stoves the water-reservoir has been composed of an outer casing open at the middle part of its bottom and containing a removable water-vessel, without any space

between them, and with the outer portion of the vessel-bottom resting on the bottom of the casing and the inner bottom part of the vessel extending through and below the bottom 5 of the casing and into the pot-holes of the rear top plate of the stove; and I do not claim anything embodied in any such reservoir cook-stoves.

I am also aware that before my invention 10 cook-stoves have been made with a water-reservoir hinged to turn horizontally upon the top pot-hole plate, and with the reservoir hinged at the middle of one of its sides about the pipe-collar, so that the reservoir could be turned 15 horizontally around the pipe-collar and off to the rear of the stove from over the pot-holes; and I do not claim anything embraced by such reservoir cook-stoves.

I also know that before my invention stoves 20 have been made with removable shelves detachably secured by lugs fitting in sockets in the turned-down side-edge parts of the pot-hole plate; and I do not claim that feature.

Also, prior to my invention a cooking-stove 25 or range had been devised with a fire-box in the middle of its front part and with two water-reservoirs, one adjoining either side of the fire-box, in the front corners of the stove or range, and immediately beneath fire-flues under a top pot-hole plate, and with the two water-reservoirs separately secured at their outer 30 rear corners by hinges to the sides of the stove or range, so that water could not be poured into and dipped out of the reservoirs 35 when they were thus directly under the fire-flues and in the places where they were to be heated, and so that water could be poured into and dipped out of the reservoirs only when they were swung on their hinges out from 40 under the fire-flues and away from the places where they were to be heated; and I do not claim anything embraced in such a stove or range.

Also, before my invention a cook-stove had 45 a main top pot-hole and over the fire box a lower pot-hole plate, upon which latter was a raised partial casing composed of a top plate, two end plates, and a front plate only, all hinged together and secured by a hinge at one 50 rear corner to one side of the stove, so that the partial casing could be swung off from over the said lower pot-hole plate. That partial casing was entirely open at one side, and therefore could not fully incase a water-vessel, 55 and did not have in its top any opening through which a water-vessel could be inserted and removed, or through which water could be poured into and dipped out of a vessel in such casing, and did not have any bottom or 60 other means whereby a water-vessel could be supported and swung off laterally by and within the partial casing from over the pot-hole plate; and I do not claim anything embodied in that construction.

65 What I claim as my invention is—

1. The combination, with a stove having

the rear top pot-hole plate, B, and a heating-flue immediately under that plate, of the water-reservoir, fitting upon that plate and over the pot-holes therein, and movable thereon, 70 and hinged at one front corner part of the reservoir to one side part of the stove, substantially as shown and described.

2. The combination, with a stove having the rear pot-hole plate and removable reservoir fitting upon said plate, of the two pairs of half-hinges c c' and d d', fast on the two front corners of the reservoir and on the two side parts of the stove, respectively, and adapted to be connected by removable pivot-pins, all substantially as described and shown. 75

3. The combination, with a stove having the rear pot-hole plate and thereon the movable water-reservoir hinged at one front corner to one side part of the stove, of the removable extension-piece F, detachably secured to the stove and helping to support the reservoir when the latter is turned off from over the pot-holes onto said extension-piece, all substantially as described. 85

4. The combination, with a stove having a rear pot-hole plate, B, over a heating-flue space, C, of a water-reservoir consisting of the inner vessel, D, and the outer casing, E', containing said vessel and supporting its bottom 90 and fitting and movable to and fro on said pot-hole plate, with a space, G, between the walls of said vessel and its casing, and the bottom of the casing being open for the passage of heated air or gas from the space C 95 into the space G, all substantially as described and shown.

5. The combination, with a stove having a rear pot-hole plate, B, over a heating-flue, C, of the movable casing E', fitting on said plate 100 over the pot-holes therein, hinged at one front corner to one side of the stove, and having walls on all sides, a top opening through which a water-vessel, D, can be inserted and removed, and a bottom, l, with opening m for supporting the bottom of the water-vessel and permitting contact therewith of heated air or gas from the stove, all substantially as shown and described. 110

6. The combination, with a stove having a rear pot-hole plate, B, and the removable casing E', fitting upon said plate and formed to receive, contain, and support a removable vessel, substantially as described, of the two pairs of half-hinges c c' and d d', fast on the two front corners of said casing and on the two side parts of the stove, respectively, and adapted to be connected by removable pivot-pins, as set forth. 115

In testimony whereof I hereunto set my hand, 120 in the presence of two subscribing witnesses, this 2d day of March, 1880.

ROBERT GALBRAITH.
